CHARLES DEMPORT, OF SOLVAY, NEW YORK.

APPARATUS FOR COVERING EARTHENWARE COCKS WITH LEAD.

1,176,134.

Specification of Letters Patent.

Patented Mar. 21, 1916.

Application filed September 14, 1915. Serial No. 50,612.

To all whom it may concern:

Be it known that I, CHARLES DEMPORT, a citizen of the United States, residing at Solvay, in the county of Onondaga and State 5 of New York, have invented certain new and useful Improvements in Apparatus for Covering Earthenware Cocks with Lead, of which the following is a specification.

This invention relates to improvements in 10 apparatus for coating or covering earthenware cocks with lead.

The various features and parts of the invention will be understood from the detailed description which follows, and by reference to the accompanying drawing in 15 which—

Figure 1 is a front-side elevation of the complete device ready for operation. Fig. 2 is an edge view of the same. Fig. 3 is a 20 vertical longitudinal section taken on line 3—3 of Fig. 1. Fig. 4 is a top plan view. Fig. 5 is a view of the earthenware cock. Fig. 6 is a view of the cock after it is 25 covered with lead. Figs. 7 and 8 are respectively an edge and a face view of one of the split cores.

Heretofore, in the manufacture of certain acids, such as nitric and sulfuric acids, lead pipes have been employed for conducting 30 the acids, and in order to be able to control the flow of the acids to and from the said pipes, earthenware valves or cocks are employed, the lead and the earthenware being the only convenient and safe materials, 35 which are not attacked or destroyed by the acids.

In order to couple or connect the earthenware cocks with the lead pipes, the ends of the lead pipe sections are expanded by suitable 40 means, particularly by heating the pipes sufficiently to allow the threaded ends of the cocks to be inserted, and securely held in place. This method of attaching the cocks to lead pipes, has always been a 45 tedious, expensive and slow job, and owing to the fragile nature of the earthenware cocks, and the force required to make the said connections, many of the cocks are broken, which entails another large and use- 50 less expense. Furthermore, after the ends of the cocks are inserted in the lead pipes

as explained, the central or body portion of the cocks being left exposed and requiring reinforcement to protect the portion between the central body portion and the 55 threaded ends from breaking, the said body portion has been covered with a sort of sleeve or jacket also composed of lead, which generally over-laps the ends of the lead pipes at the opposite sides of the plug of 60 the cock. To properly apply these jackets it requires considerable time, and besides the lead must be "burned", so as to make the joints between the jacket and the ends of the pipe acid tight. 65

My invention has for its object to provide suitable molds, in which the earthenware cocks are adjustably disposed, and then to pour into said molds molten lead for casting leaden shells or jackets upon and around the 70 whole cock at a single operation.

A detail description of my improved apparatus follows:

In the drawing, 2 and 2' represent the 75 halves or sections of a split-mold, which are preferably made of suitable metal, as cast iron, or steel, and having hollow sides, which when the sections are placed together, as shown in the drawing, form the mold-cavity 3, in which is disposed an earthenware cock, 80 as 4. Dowel-pins 5 carried by one section and entering sockets in the opposite section, serve to prevent the lateral movement of the sections 2—2' when they are put together before each casting operation. The mold 85 2—2' preferably stands up-right during the casting operations, and its lower end is supported by a block or part 6, which has a suitable recess or cavity 7 in its top-side to receive the lower ends of the mold sections, 90 the said recess preferably being circular and large enough in diameter to allow the free insertion of the mold.

8 represents a platform, table, or base, having a raised portion, or base 9, the top 95 of which is hollowed-out, as at 9' and is provided with an annular ledge 9'', upon which rests the block or plate 6. No other attaching means are provided for these parts, and the block 6 may be readily detached from 100 the table 8, and the mold may also be detached from the block 6, for the purpose of

removing the cock, after each casting operation.

Each earthenware cock 4 is hollow throughout longitudinally, and is also provided with a transverse tapering bore or opening 4', in which is disposed the usual rotatable plug or valve 10, by means of which the flow of liquid or acid to and from the cock is controlled. The plug 10, has a handle 10', and may be held in the body 4 by any suitable means. When the cock 4 is placed in a mold 2—2', it is supported therein by a core or plug 11, having a reduced portion 11' which is inserted in the lower open end of the body 4. The part 11 passes through a central perforation in the block 6, and its lower end rests upon the upper end of a screw 12, which is threaded centrally through the table 8 and the raised portion 9. The said screw has a hand-wheel 12' for manipulating said part. By this construction and arrangement of the bottom support for the cock, the turning of the screw in opposite directions adjusts the cock vertically for bringing the transverse opening 4' concentric to similar, but slightly larger, openings 13 and 14 which are formed concentrically in the opposite sides of the split mold, so that one-half of each of said openings occurs in each of the sections 2 and 2' (see Figs. 1, 2 and 3). The reduced portion 11' substantially fills or closes the bottom end of the cock 4, and prevents the molten lead from entering the cock. At the time the cock is disposed in the mold, and before the molten lead is poured, the valve-plug 10 is removed, and the whole interior of the cock is filled with sand 15, to prevent the molten lead from flowing into the interior of the earthen body. After the cock is set in position within the mold, split cores or parts 13' and 14' are inserted in the openings 13 and 14, and these are held in place with their inner ends bearing against the corresponding faces of the body 4, and concentrically to the transverse opening 4', by a bolt 16, the said cores being perforated at 16'' for the purpose. The said bolt has a tapering head 16' which enters the counter-sunk outer face of the core 13'. The opposite or threaded end of the bolt 16 receives a nut 17 having a cone-shaped portion which enters a corresponding socket in the face of the core 14'. The tightening up of the nut 17, draws the cores 13' and 14' tightly against the opposite faces of the body of the cock 4, and as the said cores are larger in diameter than the opening 4', they not only prevent the lead from entering the said opening, but also prevent the lead from approaching close enough to the said opening to touch and thereby prevent the plug 10 of the cock from properly seating in the hole 4'. The tapered head of the bolt and the tapered nut tend to slightly expand the

cores 13' and 14', so as to hold them tightly and firmly in place, and hold the earthenware cock from shifting in the mold, as well as prevent the escape of any of the lead at the said points. Before the bolt 16 is tightened-up a second plug or core 18, having a reduced lower end 18', is inserted in the open top-end of the body 4, to prevent the molten lead from entering the upper end of the cock, as well as for coring the extended portion 19' of the lead jacket 19. The core 18 is held in place by gravity. By referring to Fig. 3, it will be seen that the cores 11 and 18 are smaller in diameter than the openings in the top and bottom ends of the mold 2—2'. This provision is made so that the molten lead when poured in the mold will extend to the ends of the mold, and in doing so projects a short distance beyond the ends of the earthenware cock. This provides suitable lead extensions 19' and 19'' to which the lead conducting pipes (not shown) may be attached without interference from the earthenware. The lead piping referred to is usually secured to the terminals 19' and 19'' of the cast covering or jacket 19, by a process which is known as "burning". After the cock is disposed in the mold ready for casting the jacket or covering 19 around the cock, one of the operators places the jaws of a pair of tongs against the opposite sides of the mold 2—2', at about the positions or points indicated by the arrows 20 in Fig. 1, and he applies enough pressure to the tongs to hold the mold steady, and at the same time prevent the sections 2—2' from spreading apart, while another operator pours the molten lead from a ladle 21 into the top opening 22, which encircles the upper core 18, as indicated in Fig. 3. The dotted lines in Fig. 1, show the manner in which the mold sections 2 and 2' may be separated for inserting and removing the earthenware cocks.

My method and apparatus for casting a lead jacket or covering upon earthenware cocks is extremely simple, and the cocks can be covered more rapidly and at about one-fourth the expense, as compared with the old or prevailing method of doing such work, and the said work may be performed without any waste or loss from breakage of the fragile cocks. After the earthenware cocks are covered, as herein shown and described, they stand considerable rough handling and last a long time, which effect still a further saving. When the cocks have served their usefulness, the lead is reclaimed and re-molded, and may be used for any suitable purpose without appreciable waste.

Having thus described my invention, what I claim as new and desire to secure by Letters Patent, is—

1. An apparatus for incasing earthenware cocks with lead comprising a split mold

- adapted to receive an earthenware cock, means including a base for supporting the said mold in up-right position, a core disposed in the bottom of the mold adapted to be inserted part way in the lower end of the cock, a screw carried by said base for adjusting said core for raising and lowering the cock, a core disposed in the open top of the said mold and adapted to be partially inserted in the opposite end of the cock; and a pair of cores inserted in openings arranged midway between the ends of the mold sections for adjustably holding the body portion of the cock in place.
2. In an apparatus for casting a lead covering upon earthenware cocks, the combination with the split mold adapted to receive a cock, of means for supporting said mold in up-right position, a core disposed in the lower open end of the mold whereby to be inserted part way into the lower end of the cock, suitably supported screw threaded means adjustably supporting said core, split cores inserted through openings in the opposite sides of the mold for adjusting the cock laterally, and a core disposed in the open top of said mold and adapted to be inserted part way into the top end of said cock.
3. An apparatus for casting lead jackets on earthenware cocks, comprising a pair of mold sections adapted to be joined together for forming the mold cavity therebetween adapted to receive a cock, the opposite ends of said mold being open, a block for supporting the bottom end of the mold sections, a base for supporting said block, a screw carried by said base, a core piercing the said block for supporting the lower end of the cock, said core resting upon said screw, a pair of split-cores inserted through openings in the opposite sides of the said mold sections, a bolt for holding said split cores in place, a core inserted in the open top of the mold and adapted to be partially inserted in the top end of said cock, the said top and bottom cores adapted for coring the projecting ends of the lead jackets.
4. In an apparatus for casting a lead jacket around earthenware cocks, the combination with the split mold adapted to inclose a cock of smaller size than the cavity of the said mold, of means including a base for supporting said mold, a screw threaded through the said base concentric to the said cock, a core adjustably supported by said screw for supporting said cock, and a pair of split cores disposed in openings in the opposite sides of the mold and adapted to engage the opposite sides of said cock, for adjustably holding the cock in the said mold.
5. In an apparatus for casting a lead jacket around earthenware cocks, the combination with the split mold adapted to receive a cock, of a base for said mold, a screw threaded through the said base concentric to the said cock, a core supported by said screw and adapted to support the cock, a pair of split cores disposed in openings in the opposite sides of the mold and adapted to engage the opposite sides of said cock, and a bolt piercing the said split cores and also the mold and adapted to engage the said cock for holding the cock concentrically in the said mold.
6. In an apparatus of the class described, the combination of a pair of mold sections adapted for inclosing an earthenware cock and having a mold cavity longer and broader than said cock, the opposite ends of said cavity being open, cores disposed in the open ends of the mold cavity and adapted to engage the opposite ends of the cock, a screw engaging one of said cores for adjusting said cock longitudinally, and split cores disposed in the openings in the opposite sides of said mold sections for adjusting said cock laterally.
7. In an apparatus of the class described, the combination of a pair of mold sections adapted for enveloping an earthenware cock and having a mold cavity larger than the said cock, and having openings mid-way between the ends thereof, the opposite ends of the said cavity being open, a support for said mold sections, a core piercing the said support and adapted to engage the bottom end of the cock, means for adjusting said core vertically, means inserted in the openings in the opposite sides of the said mold sections adapted to adjust the cock laterally, and means for preventing molten lead when poured into the mold cavity from entering the interior of the cock.
8. In an apparatus of the character described, the combination of a split mold, means for supporting the mold in upright position, a core disposed in the bottom of the mold, screw means for adjusting said core, a core disposed at the top of the mold, and a pair of cores inserted in openings substantially midway between the ends of the mold sections.
9. In an apparatus of the character described, the combination of a sectional mold for cocks or the like, longitudinally extending internal cores at the ends of the mold, one of said cores being lengthwise adjustable, and transversely extending cores projecting inwardly from the sides of the mold.
10. In an apparatus of the character described, the combination of a sectional mold for cocks or the like, longitudinally extending internal cores at the ends of the mold, said cores being adapted to engage opposite ends of a cock or the like positioned in the mold, and transversely extending cores projecting inwardly from the sides of the mold to engage the sides of the cock, said trans-

versely extending cores being relatively adjustable.

11. In an apparatus of the character described, the combination of a sectional mold for cocks or the like, internal end cores for the mold, means operable from without the mold for lengthwise adjusting one of said

end cores, transversely extending cores intermediate the ends of the mold sections to engage the sides of the cock, and means 10 operable without the mold for relatively adjusting said transverse cores.

In testimony whereof I affix my signature.

CHARLES DEMPORT.
